INDIVIDUAL VERTICAL-TYPE FUEL-BURNING HEATER

William G. Carter, Monrovia, Calif., assignor, by
mesne assignments, to Affiliated Gas Equipment,
Inc., Cleveland, Ohio, a corporation of
Delaware

Application May 7, 1948, Serial No. 25,763

11 Claims. (Cl. 126—91)

1 The invention relates to heaters ordinarily referred to as space heaters, and in this instance the heater is one utilizing a gas burner supplied with any one of a variety of types of gas.

Space heaters of a general sort are a familiar accessory for the heating of dwelling houses and other buildings where unit heaters are found most advantageous. Although the original space heaters utilized for fuel such substances as wood and coal, with the advent of inexpensive gas as a fuel supply considerable attention has been directed to the provision of gas fired space heaters individually operated and controlled so that, if need be, individual thermostats located in the room or space to be heated can be connected with the gas supply line for the control of such gas fired space heaters.

Heretofore, however, convention has dictated to a large extent the form and mechanical construction of gas fired space heaters. To a large extent they have been patterned after the form and proportions of stoves and cabinet heaters. When following that pattern, the heaters are built low and the gas burner is customarily of an elongated type so that the flame is spread over a considerable area in a horizontal direction while at the same time being confined to a relatively narrow width so that the space heater does not occupy any more floor space than necessary.

Other types of gas fired space heaters have been relatively uneconomical of floor space in that they have been built large and bulky with a great number of burners located therein in order theoretically to generate enough heat to warm a space of given volume.

Some departure has recently been made from the conventional type of gas fired space heater wherein vertical heater tubes have been employed supplied with heat individually by a gas burner at the base of the tube. Heretofore these vertical type heaters have been constructed in a manner permitting them to be built into the wall of a room or other space to be heated. There are frequent instances, however, where it becomes inadvisable to locate such a vertical type heater within the building wall and consequently resort must be had to some type of space heater which can be set out away from the wall. The invention disclosed herein is directed to a space heater which retains the advantages of the vertical type space heaters heretofore constructed for mounting within a building wall and which incorporates additional features productive of a space heater which can be set away from the wall and at the same time provide a convenient, inexpensive and highly efficient device which

need occupy no more than a minimum area of available floor space.

It is therefore among the objects of the invention to provide a new and improved unit type vertical space heater, adapted to utilize heating tubes or elements, which is simple in design, inexpensive in construction, and easy of installation.

Another object of the invention is to provide a new and improved unit type vertical space heater incorporating one or more heating tubes and provided with an efficient reflector, the elements comprising the space heater being kept substantially to a minimum without impairing the efficiency or safety features made necessary by the use of a device of the class described.

Still another object of the invention is to provide a new and improved unit type vertical space heater utilizing one or more heater tubes and incorporating a reflector for heat which is capable of adjustment about the heating tube in order to direct the distribution of heat toward an area where the maximum heating effect may be desired.

25 A further object of the invention is to provide a unit type vertical space heater wherein heavy items of equipment, such as the burner and appropriate accessories, are located compactly within a chamber of relatively small dimensions at the base, the proportions of which in a lateral direction are confined to an area no greater than that occupied by an elongated vertical heating tube and reflector member which, although of a considerable height in proportion to its width, remains stable in erected position with portions thereof properly shielded for protection against the heating tube which provides the source for radiation of heat.

30 A still further object of the invention is to provide in a unit type vertical space heater a new and improved reflector capable of adjustment about a vertical heating tube and which, moreover, is so constructed that heat radiating from the rear of the tube may be properly reflected out into the space to be heated with substantially the same effectiveness as heat radiated from the front of the heater tube immediately facing the space to be heated.

35 Still another object of the invention is to provide a new and improved unit type vertical heating tube wherein the tube itself at its outlet end is formed so as to provide portions of a down-draft diverter in order thereby to minimize the number of parts comprising the venting portion of the device.

With these and other objects in view, the

Invention consists in the construction, arrangement and combination of the various parts of the device whereby the objects contemplated are attained, as hereinafter set forth, pointed out in the appended claims and illustrated in the accompanying drawings.

In the drawings:

Figure 1 is a front elevational view of the device with portions of the guards broken away to show the structure of the heating tube and reflector.

Figure 2 is a cross-sectional view taken on the line 2—2 of Figure 1.

Figure 3 is a cross-sectional view similar to Figure 2 showing the reflector in a different position of adjustment.

Figure 4 is a vertical sectional view drawn to a larger scale taken on the line 4—4 of Figure 1.

Figure 5 is a vertical sectional view drawn to a larger scale taken on the line 5—5 of Figure 1.

Figure 6 is a cross-sectional view taken on the line 6—6 of Figure 5.

Figure 7 is a fragmentary vertical sectional view taken on the line 7—7 of Figure 3.

In the construction and fabrication of gas fired space heaters certain elements are absolutely essential to the functioning of the device. When space heaters are designed to utilize a gas burner as a source of heat there is obviously one very hot area in the heater and suitable safe-guards must be provided in order to minimize the danger of overheating at this point. Naturally also if such a gas fired heater is to be efficient, means must be provided for dispersing heat from the heat source uniformly into an area or space to be heated. In the unit type vertical space heaters embodying this invention the source of heat is located in a vertical heating tube or column wherein the hot combustion gases preferably are momentarily restrained in their flow so that the whole tube becomes a source of heat. In order, however, to make the heater effective as a space heater, reflectors must be utilized to direct radiating heat from the wall of the heating tube facing away from the space to be heated back into that space.

Because of the fact that combustion gases are generated by the burner for passing through the heating tube, some means must be provided for accumulating the hot combustion gases after the heat therefrom has been utilized and directing them upwardly or outwardly at some specified location. In some types of dwellings or other spaces to be heated the products of combustion can be vented into the space. On other occasions a vent conduit is found more advantageous for leading the products of combustion out of the room into the atmosphere. In either event some type of collecting hood need be provided near the outlet for gases from the heating element. Where space heaters are to be used it becomes highly advantageous to so construct the various parts that wherever possible they may serve a multiple purpose and thereby minimize the quantity of metal parts used for the structure while at the same time preserving all of the safety features which are so necessary when gas burners are used for heating purposes.

In the embodiment chosen to illustrate the invention there is shown a unit type vertical space heater comprising a base 10 having a footing 11 adapted to rest upon the floor and above which is a wall portion 12 within which are located the burner and suitable accessories needed for the combustion of gas. Mounted above the base is a heating tube or column 13 with which is asso-

ciated a concave reflector assembly 14 partially surrounding the tube and at the top is a hood 15 terminating in a vent 16. A guard for the tube is here illustrated as comprising vertical grill rods 17 surrounding the heating tube on the sides not occupied by the reflector 14.

As illustrated in greater detail in Figure 5, the base 10 and the wall portion 12 surmounting the base are illustrated as housing the functional parts of the gas burner mechanism in a compact arrangement. The wall portion 12 is here illustrated as cylindrical in form providing a space 20 and within the space 20 is an interior wall 21 which forms an inner combustion chamber 22.

10 The inner combustion chamber, however, extends only part way down with respect to the chamber 20 and is, moreover, provided with a horizontal partition 23 forming a segmental bottom only partially closing the combustion chamber below the burner. One side 24 of the wall 21 may be flat and inset as illustrated in Figures 5 and 6.

20 Within the base is located a block here designated as a conduit block 25 or manifold secured to the footing 11 by means of a bolt 26. At the center of the manifold there is provided a means for mounting a burner 27 of any suitable design and a boss 28 having a bore extending therethrough providing means for mounting a shut-off valve 29 supplied through a gas line 30 with gas from a main 31. The shut-off valve is mounted low on the base so that its weight contributes to the weight of the manifold at the lowest point possible in the device. The valve is illustrated as being located well within the circumference of the wall portion 12 so that only a handle 32 protrudes.

30 Within the wall portion 12 on the side of the burner opposite the shut-off valve there may be provided a pressure regulator 33 in a gas line with a vent tube 34 connected between the burner and the pressure regulator. The regulator is supported upon a bracket 35 bolted to the top side of the conduit block or manifold. These mechanisms are of conventional construction but are referred to herein for the purpose of describing a complete operating device and to direct attention to the compact arrangement of these heavy operating portions of the device all located near the floor.

40 Also mounted upon the manifold is a pilot tube 35 topped with a pilot burner 36 adjacent the main burner. A supply line 37 feeds the pilot from the inlet side of the shut-off valve so that the pilot always remains burning. A pilot adjusting valve 38 is adapted to be adjusted for setting the height of the pilot flame. A door 40 hinged at 41 is adapted to swing open to provide access to the burner, the pilot and particularly the control for the pilot.

50 At the top of the combustion chamber there is provided a cover piece 45 which fits around the upper edge of the wall 21, thereby closing the top of the combustion chamber except for a central circular aperture formed by a flange 46 of the cover piece. The heating tube or column 13 is adapted to fit within the flange 46 and to communicate with the combustion chamber 22 through the cover piece 45 at the central aperture. It should be noted also that a substantially annular opening 47 appears at the top of the wall portion 12 so that air from below may circulate between the walls 12 and 21 upwardly and outwardly through the annular opening 47. This 60 construction will provide a suitable insulation

around the wall 21 of the combustion chamber which during operation becomes heated.

The cover piece 45 is specially constructed so that it includes a horizontal annular ledge 48 spaced some distance from the flange 46. This ledge is adapted to provide a bearing or support for a lower end element 49. An examination of Figure 5 will reveal that the lower end element is provided with an outer flange 50 and an inner flange 51 for strengthening purposes, the latter flange being located approximately within the area of the ledge 48. Ventilating holes 54 are also provided in the lower end element.

In order to secure the lower end element 49 in position upon the ledge, there is provided an annular clip 52 attached by screws to the cover piece 45 and having an outer portion 53 which overlies the flange 51, thereby securely holding the lower end element in place but at the same time permitting rotation of the lower end element about an axis extending through the center of the heating tube 13. The lower end element 49, resting on the ledge 48 of the chamber cover piece 45, by thus encircling the heating tube 13, limits horizontal separation of the bottom portion of the reflector assembly from the heating element 13, while still permitting the above mentioned rotation. Provision for rotation of the lower end element contributes materially to the operation of the reflector 14.

The reflector assembly 14 itself comprises in addition to the lower end element 49 an upper end element 60 having the same outside diameter but constructed of multiple plates 61 and 62 secured together and having outer flanges 63. The plate 61 extends inwardly and provides a horizontal flange 64 adapted to cooperate with another flange piece 65 to provide an annular recess for an asbestos sealing band 66. The band serves partly as an air seal and partly as a non-metallic bearing surface, while the element 60 itself, by encircling the heating element 13, limits horizontal separation of the upper end of the reflector assembly 14 from the heating element 13. Thus, the two end elements 49 and 60 together serve to restrict or limit horizontal separation of the reflector assembly from the heating element 13.

Between the upper and lower end elements the reflector assembly 14 includes an outer casing 67 semi-circular in shape, as is particularly evident in Figures 2 and 3, the outer casing being securely held by the outermost flanges of the upper and lower end elements. Within the outer casing there is located a reflector sheet or member 68 preferably having a special wing form best illustrated in Figures 2 and 3. The reflector sheet is shown secured at its outermost edges to adjacent edges of the outer casing 67 so that the reflector sheet and the outer casing are secured together as a unit. It will be apparent from the foregoing description that the entire reflector member incorporating the upper and lower end elements, the outer casing, reflector sheet, and grill rods is adapted to rotate about the stationary heating column 13. The reflector sheet is spaced inwardly from the casing 67.

If desired, the extent of rotation of the reflector may be limited by suitable stops. In the embodiment illustrated, the stops comprise ends 70 and 71 of a cut-out portion of the annular clip 52, this cut-out portion in the present instance being approximately 45 degrees. An upwardly bent ear or leg 72 on the inner flange 51 of the lower end element may be located so

as to extend upwardly into the cut-out portion at a position where it will abut against either the end 70 or 71 at one extreme or another of rotation of the reflector.

Attention is also directed to the unique construction of the reflector sheet 68. As here shown it consists of right and left-hand parts 73 and 74, the form of which can be readily discerned in Figures 2 and 3. The left and right-hand parts are joined by a vertical rib 75 which is in actuality a raised portion of the sheet of material forming the reflector. Both left and right-hand parts are irregularly concave with a relatively sharp radius of curvature adjacent the rib diverging progressively outwardly toward the outer vertical edges. By so constructing the reflector, radiant heat generated on the rear of the heating tube facing the reflector is reflected outwardly through the space between the heating tube and the reflector and thereby out into the area to be heated. This construction avoids as much as possible reflecting heat from the heating tube immediately back against the heating tube itself which would result in overheating the rear side of the tube and a corresponding lowering of the efficiency of the device for heating purposes.

Also as shown the heating tube is illustrated as being provided with indentations 76 which in the present illustration comprise two in number 30 on the front facing away from the reflector and two in number on the rear facing the reflector when the reflector is in normal position as shown in Figure 2. A baffle 77 inside the tube provides two separate passages for the products of combustion as they pass upwardly from the burner 27 to an outlet 78 at the top of the heating tube. In this instance the baffle 77 has a lip 79 at the top end bent over and attached to an adjacent portion of the heating tube. A heating tube of 40 the general character shown and described is shown and claimed in my U. S. Patent No. 1,991,788, granted February 19, 1935.

The upper structure of the space heater has considerable significance in that the entire upper structure is mounted upon and secured to the upper end or top of the heater stationary heating tube 13 and offers no interference to rotational positioning of the reflector. As shown, the upper structure consists of an outer hood member 80, an edge 81 of which has substantially the same diameter as the outermost flange of the top end element. An inner hood member 82, circular at the top, has a somewhat elliptical skirt, the bottom edges of which are secured to the upper or outlet end 70 of the heating tube. There is thus formed an annular space 83 between the inner hood and the outer hood member 80. This space is vented by apertures 83' in the top of the outer hood 80. These hood members are attached together at their respective flanges 84 and 85 which surround a vent aperture 86 centrally located with respect to the heating tube. In the present instance a vent pipe 16 is attached to the flange 84 but this pipe may be removed if desired for replacement with a vent grill, or the passage 86 may be left open, depending upon operating conditions.

Within the innermost hood member 82 there is located directly above the heating tube a deflector 90 having wings 91 held in place by welding to the member 82. As shown the deflector is in the shape of a V throughout the portion which spans the outlet 78 of the heating tube. Cooperating with the deflector 90 are inwardly bent portions 92 and 93 of the heating

tube. These inwardly bent portions form deflecting portions of a down-draft diverter. The form of the inwardly bent portions is most readily apparent from an examination of Figures 1 and 4. During a down-draft or back-draft through the vent opening 86 cooperation of the deflector 90, the inner hood member 82, and the inwardly bent portions 92 and 93 of the heating tube effectively deflects the down-draft away from the interior of the heating tube and outwardly into the atmosphere between the top element 60 of the reflector and the lower edges of the hood members 80 and 82.

It is believed that operation of the device is readily apparent from a perusal of the foregoing description. To summarize briefly there is provided a vertical type gas heater having the gas burner located in the base. When the burner 27 is ignited the heating tube 13 is heated substantially uniformly throughout its entire area by hot products of combustion passing upwardly through the tube on either side of the baffle 71 and being guided thereby into contact with the indentations 76. When the tube is hot, some heat will be radiated directly from the tube into the space to be heated and the reflector comprising particularly the left and right-hand parts 73 and 74 will assist materially in reflecting substantially all the remaining rays of the heat which strike the reflector out into the space to be heated. If more heat is desired in one direction than another, the reflector can be rotated about the tube a limited amount as determined by the stops 70 and 71. The asbestos band 66 provides a bearing for the upper end element of the reflector against the hot outer surface of the tube. The lower end element 49 of the reflector provides a rotatable support for the reflector upon the cover piece 45 which in essence is a part of the base. An element in the successful operation of the structure involving the reflector lies in the fact that the center of rotation of the reflector is the same as the axis of the heating tube. Constructed in this manner the distance between the surface of the heating tube and any given area of the reflecting surfaces of the reflector will remain the same for all adjustments of the reflector.

The top of the heater includes a construction which satisfies the requirements of draft hood action necessary to most normal venting arrangements for heaters of this general description. To that end the outer hood member 80 is provided adjacent the top with the apertures 83'. Although the normal draft hood action would take place without the presence of the outer hood member, nevertheless the presence of this member improves the appearance of the device and also contributes to insulating the hotter portion of the collecting box defined primarily by the inner hood 82.

A noteworthy feature of the present device lies in the fact that the hood and vent means are carried entirely by the heating element itself and supported thereby upon the base. Contributing also to the economy of the structure and efficiency of operation of the device is the downdraft diverter consisting to a large extent of the inwardly bent portions of the heating tube itself which with the assistance of a single deflector member located thereabove effectively avoid downdrafts being directed into the heating tube. Aiding measurably in this is the incorporation of a downwardly directed curve at the middle of the deflector 90 by means of which the lower edge of the

deflector more closely approximates the shape of the opening at the top of the heating tube.

Also of interest is the proportioning and disposition of the heating element 13 and the reflector assembly 14. It will be noted in Figure 2 that a vertical, chordal plane spanning the vertical edges of the concave reflector assembly 14 would approximately bisect the cylindrical heating element 13, whereby a substantial portion, in this case, approximately half, of the heating element 13 would lie outside the region bounded by the reflector assembly 14 and the spanning chordal plane. The advantage of this structure is that there results direct radiation over a full 180° arc, thereby enabling direct radiant heat to reach into the corners of the room on each side of the heater. The protruding or projecting nature of this half of the heating element 13 also results in cooler heater operation with consequent increased efficiency.

While I have herein shown and described my invention in what I have conceived to be the most practical and preferred embodiment, it is recognized that departures may be made therefrom within the scope of my invention, which is not to be limited to the details disclosed herein but is to be accorded the full scope of the claims so as to embrace any and all equivalent devices.

Having described my invention, what I claim as new and desire to secure by Letters Patent is:

1. In a vertical-type space heater, a base assembly comprising walls forming a combustion chamber, a gas burner disposed in said combustion chamber, a hollow, vertical, tubular heating element fixedly supported upon the base assembly communicating at its lower end with the combustion chamber above the burner, a vent above the upper end of the heating element, a reflector assembly including a reflector extending substantially throughout the height of said heating element and partially therearound, upper and lower end elements fixed to said reflector and encircling said heating element to limit horizontal separation of said assembly from said heating element, and means for rotatably supporting said reflector assembly by said base assembly for rotatable adjustment about the axis of said heating element.

2. In a vertical type space heater a base assembly comprising walls forming a combustion chamber, a gas burner disposed in said combustion chamber, a hollow vertical tubular heating element fixedly supported upon the base assembly communicating at its lower end with the combustion chamber about the burner, a hood including a vent carried upon the upper end of said heating element, a reflector assembly including a reflector extending substantially throughout the height of said heating element and partially therearound, upper and lower end elements fixed to said reflector and encircling said heating element to limit horizontal separation of said assembly from said heating element, said lower end element being rotatably supported by said base assembly whereby said reflector assembly is rotatably adjustable about the axis of said heating element.

3. In a vertical type space heater a base assembly comprising walls forming a combustion chamber, a gas burner disposed in said combustion chamber, a hollow vertical tubular heating element fixedly supported upon the base assembly communicating at its lower end with the combustion chamber about the burner, a hood including a vent carried upon the upper end of said

heating element, a reflector assembly including a reflector extending substantially throughout the height of said heating element and partially therearound, upper and lower end elements fixed to said reflector and encircling said heating element to limit horizontal separation of said assembly from said heating element, said lower end element being rotatably supported by said base assembly whereby said reflector assembly is rotatably adjustable about the axis of said heating element, and limit stop elements on said base assembly and said reflector assembly, respectively, adapted to mutually engage to limit the extent of rotatable adjustment of said reflector assembly about said heating element.

4. In a vertical type space heater a base assembly comprising walls forming a combustion chamber, a gas burner disposed in said combustion chamber, a hollow vertical tubular heating element fixedly supported upon the base assembly communicating at its lower end with the combustion chamber about the burner, a hood including a vent carried centrally upon the upper end of said heating element, a reflector assembly including a curved reflector extending substantially throughout the height of said heating element and partially therearound, upper and lower end elements fixed to said reflector and encircling said heating element to limit horizontal separation of said assembly from said heating element, said lower end element being rotatably supported by said base assembly whereby said reflector assembly is rotatably adjustable about the axis of said heating element, guard means extending between said end elements on the side of said heating element unoccupied by said reflector and limit stop elements on said base assembly and said lower end element, respectively, adapted to mutually engage to limit the extent of rotatable adjustment of said reflector assembly about said heating element.

5. A space heater comprising: a base member, means fixedly mounted on said base member forming a combustion chamber and providing a support for a heating element and a reflector assembly, a fuel burner mounted within the combustion chamber, a hollow tubular heating element fixedly mounted on said means on an axis passing through said chamber and having one end open to said combustion chamber, a reflector assembly behind and substantially coextensive with the length of the heating element, and means rotatably mounting said assembly on said first means for rotatable adjustment about said axis.

6. A space heater comprising: a base member, means fixedly mounted on said base member forming a combustion chamber and providing a support for a heating element and a reflector assembly, a fluid fuel burner mounted within the combustion chamber, a hollow tubular heating element fixedly mounted on said combustion chamber means on an axis passing through said chamber and having one end open to said combustion chamber, a hood forming products of combustion collecting box fixedly mounted upon the other end of said heating element and supported thereby, a reflector assembly behind and substantially coextensive with the length of the heating element, and means rotatably mounting said assembly, on said combustion chamber means for rotatable adjustment about said axis, there being a clearance between the end of said reflector adjacent said hood and said hood so that the hood does not interfere with rotation of the reflector and to provide an air and gas passage be-

tween the edge of the hood and the end of the reflector assembly.

7. A space heater comprising: a base assembly including a wall forming a combustion chamber and an upper outlet opening therefor, and means above said wall and fixed thereto adapted to support a heating element and a reflector assembly, a burner in said combustion chamber, a hollow tubular heating element supported on said support means on an axis passing through said chamber and open at one end to said combustion chamber through said outlet opening, a reflector assembly including a concave reflector behind and substantially coextensive with the length of the heating element, and means rotatably mounting said reflector assembly on said support means for rotatable adjustment about said axis.

8. A space heater comprising a base assembly, a gas burner mounted in said assembly, a hollow tubular heating element supported on said assembly on a vertical axis in position to receive products of combustion from said burner, gas collecting means supported by said heating element at the upper end region thereof, a reflector assembly including a vertical reflector partially surrounding said heating element and substantially coextensive with the length thereof, and means rotatably mounting said reflector assembly on said base assembly for rotatable adjustment about said axis, said gas collecting means being spaced above the upper end of said reflector.

9. In a vertical type space heater, means forming a combustion chamber, a gas burner in the chamber, a heating tube fixedly mounted on said chamber means along a vertical axis and having its lower end in communication with the burner chamber to receive products of combustion from the burner, a vertical reflector partially surrounding said tube and substantially coextensive therewith, and lower and upper end elements attached to said reflector, the lower end element encircling the tube above the burner chamber and being rotatably adjustable about said axis, the upper end element rotatably engaging the tube to sustain the reflector in upright position.

10. In a vertical type space heater, means forming a combustion chamber, a gas burner in the chamber, a heating tube mounted on said chamber means along a fixed vertical axis and having its lower end in communication with the burner chamber to receive products of combustion from the burner, a vertical reflector partially surrounding said tube and substantially coextensive therewith, and lower and upper end elements attached to the reflector, the lower end element encircling the tube above the burner chamber and being rotatably adjustable about said axis, the upper end element engaging the tube to sustain the reflector in upright position.

11. In a vertical type space heater, means forming a combustion chamber, a gas burner in the chamber, a heating tube mounted on said chamber means along a fixed vertical axis and having its lower end in communication with the burner chamber to receive products of combustion from the burner, a vertical reflector partially surrounding said tube and substantially coextensive in length therewith, lower and upper end elements attached to the reflector, the lower end element encircling the tube above the burner chamber and being rotatably adjustable about said axis, the upper end element engaging the

11

tube to sustain the reflector in upright position, and gas collecting means supported by said tube above the upper end of the reflector and spaced from the reflector without direct connection thereto.
